[57] CLAIM

The ornamental design for a circuit board, as shown and described.

DESCRIPTION

FIG. 1 is a perspective view of a circuit board showing my new design;

FIG. 2 is a top plan view of the assembly of FIG. 2;

FIG. 3 is a front elevational view of the assembly of FIG. 2;

FIG. 4 is a right side elevational view of the assembly of FIG. 2;

FIG. 5 is a left side elevational view of the assembly of FIG. 2;

FIG. 6 is a rear elevational view of the assembly of FIG. 2; and,

FIG. 7 is a bottom plan view of the assembly of FIG. 2.

The broken lines shown in all figures are for illustrative purposes only and form no part of the claimed design.
